UNITED STATES PATENT OFFICE.

EUGENE MUNGER, OF BIRMINGHAM, ALABAMA, ASSIGNOR TO CONTINENTAL GIN COMPANY, A CORPORATION OF DELAWARE.

COTTON-GIN LINT FLUE.

Application filed June 3, 1925. Serial No. 34,723.

My invention relates to certain new and useful improvements in cotton gin lint flues.

In the operation of lint flues for gin batteries, difficulty has been experienced in preventing a whirling of the lint in the flue or a tendency to accumulate more on one side than on the other of the lint flue before being discharged into the condenser. Under such conditions what may be termed an unbalanced bat results which cannot be handled so satisfactorily as a bat of balanced size with respect to a longitudinal vertical plane through the center of the lint flue at the point of its discharge into the condenser. 10 Various means have been employed for controlling the discharge of lint from the several gins of the battery into the lint flue so as to balance the lint in the flue, adjustable baffles or deflectors being usually employed for this purpose, but there are many practical operating objections to these deflectors or baffles and I have conceived that the control and regulation of the flow of lint from the lint flue into the condenser can be best 15 controlled by the provision in a gin flue connection of a deflecting nozzle rotatably adjustable in such connection and having its discharge end disposed so as to direct the lint from such connection into any desired portion of the lint flue, considered transversely thereof, so as to effect a balancing or equalization of the flow of lint into the condenser. 20

It is a particular advantage of my invention that the gin flue connections can enter the bottom of the lint flue, instead of the sides, thereby avoiding by transverse currents whirls or eddies in the lint. Moreover, my preferred arrangement permits the control to be effected by the allocation of the lint from one gin, preferably the gin next to the condenser, where it will effect the desired balancing of the lint flow to the condenser. 25

My invention further contemplates novel and effective means for mounting the regulating deflector nozzle in the controlling gin flue connection with a part thereof exposed so that it can be adjusted by hand without interfering with the connection between the gin and lint flues. 30

My invention also comprises the novel details of construction for the connection between the gin and lint flues in which the regulating deflector nozzle works and with

which is associated means for locking it in any desired adjustment. 55

My invention also comprises the novel details of construction and arrangements of parts, which in their preferred embodiment only are illustrated in the accompanying 60 drawings which form a part of this specification, and in which:—

Fig. 1 is an elevation of a cotton gin lint flue showing several gin flue connections therewith adjacent to its upturned end 65 which leads to the condenser, not shown.

Fig. 2 is a cross-sectional view taken on the line 2—2 of Fig. 1, the dotted line showing the level of a balanced flow of lint therethrough and the arrows showing with reference to the extreme dotted positions of the deflector the various directions in which the lint from one of the gins may be directed by mean positions of the deflector to maintain the balanced flow through the lint flue. 70

Fig. 3 is a longitudinal cross-sectional view through the lint flue and the gin flue connection with the deflecting nozzle shown in side elevation. 75

Figs. 4 and 5 are plan and side detail 80 views of the deflecting nozzle.

Fig. 6 is a fragmental cross-sectional view, enlarged, taken on the line 6—6 of Fig. 3.

Fig. 7 is an enlarged fragmental longitudinal sectional view through the joint between the gin flue and the deflecting nozzle. 85

Similar reference numerals refer to similar parts throughout the drawings.

In the embodiment of my invention illustrated, I show a cotton gin lint flue 1 which may be termed the trunk flue, having a plurality of gin flue connections 2 and 2^a leading thereto, one from each of the several gin units of a battery. The gins are omitted, as they are not necessary for an understanding of this invention. It will be noted that the gin flues 2 and 2^a lead upwardly at an incline in the direction of flow of lint in the trunk flue and are connected separately to the bottom of the trunk flue. Theoretically, these gin flues should deliver their lint so that it would flow in the trunk flue in a balanced condition with equal volume on each side of a longitudinal vertical central plane through the trunk flue, but as a matter of fact, experience teaches that such a balanced flow of lint will not be found to 90 95 100 105

exist when the lint is discharged from the lint flue into the condenser, not shown. It is the purpose of my invention to utilize the output of lint from one or more gins, but generally the lint from the gin nearest the condenser will balance the flow of lint to the condenser, and to this end the gin flue 2^a from this end gin has its discharge end telescoped into the cylindrical end 3 of the regulating deflector which has an angularly disposed nozzle 4. This deflecting nozzle, as shown in Figs. 3 and 4, has its axis disposed at an obtuse angle to the axis of the end 3, and is cut away on a plane at an acute angle to its axis, which angle corresponds to the angle of approach of the gin flue to the lint flue, so that when the nozzle is set in its intermediate position, its upper edge will lie in a horizontal plane substantially level with the bottom of the lint flue. In such position the nozzle will discharge its lint into the lint flue exactly like the other gin flues except that it will be diverted upwardly at a greater angle. The cylindrical end 3 of the deflector is received in a pipe or flue 5 which forms a co-axial enlarged continuation of the gin flue 2^a. This flue 5 has a ring 6 interposed between it and the casing 2^a and rivets 7 rigidly connect these parts. The deflector end 3 will fit snugly into the space thus provided between the flues 5 and 2^a and is held in position by rings 8 and 9 riveted to its outer side. This arrangement is shown more fully in Fig. 7, and affords a closely fitted tight joint which yet leaves the deflector 3 free to rotate about the end of the flue 2^a.

An operating stud screw 10 is inserted through an elongated transverse slot 11 in the casing 5 and is screwed into the ring 8 which is fast on the nozzle end 3 and its outer end being exposed furnishes a tool grip by means of which the nozzle end 3 can be engaged and adjusted. The screw will be engaged in one of a series of threaded holes 12 in the ring 8, which holes are equi-distant and spaced on centers less than the length of the slot 11 so that as the nozzle is moved the full length of the slot a new hole 12 appears to receive the stud screw and permit of further adjustment.

Having assembled the deflecting nozzle in the manner described, the operator, through observance of the flow of lint through windows 13 in the trunk flue, can determine to which side of the trunk flue it is desired to deflect the balancing flow of lint through the gin connection 2^a and by easing up on set screw 10 and engaging it with a suitable tool the nozzle can be thereby rotated about the axis of the connection 2^a until the deflecting nozzle 4 has its axis pointing in the direction which will deliver the balancing flow of lint where it will produce a balanced flow in the trunk flue. When this balanced

condition has been obtained the set screw 10 can be screwed in tight when it will bind on the casing or fixed pipe 5 and hold the nozzle in the desired adjusted position. For the full range of adjustment the screw may have to be transferred to a number of the threaded holes 12 in the nozzle ring 8. Whenever for any reason it appears that the bat is not entering the condenser in balanced size this regulating deflector can be again adjusted until the balance is restored. It will be noted that all of the gin flue connections enter along the center at the bottom of the trunk flue and at an angle disposed in the direction of the flow of lint therethrough. I thus avoid any tendency of the entering blasts of lint laden air to produce whirls and eliminate the necessity of long guides or deflectors in the trunk flue.

It will be observed that the nozzle end 4 of the deflector is not reduced in cross-sectional area as the flow of lint therethrough should not be in anywise restricted. While I have shown only one of the gin flue connections provided with a balancing deflector, it is to be understood that as many of such deflectors may be employed as are required for balancing the flow of lint for the trunk flue.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

It is within the contemplation of my invention that the novel type of deflector shall be applied to the discharge end of any gin flue or lint flue where occasion exists for the deflection of the lint being discharged for the purpose of regulating a bat in the condenser.

Having thus described my invention, what I claim as new and desire to secure by Letters Patent, is:—

1. The combination with a lint flue, of a gin flue connection, and a deflector means adjustable about the axis of the discharge end of said gin flue connection for deflecting the lint therefrom into the desired portion of the lint flue.

2. The combination with a lint flue for conveying lint from a battery of gins to a condenser, of a plurality of gin flue connections, and a deflector means adjustable about the axis of the discharge end of one of said gin flue connections for deflecting the lint therefrom into the desired portion of the lint flue.

3. The combination with a lint flue, of a gin flue connection entering the lint flue at an acute angle to the direction of the flow of lint in the lint flue and having a rotat-

able discharge end carrying an angularly disposed deflector.

4. The combination with a lint flue, of a gin flue connection having interposed in its discharge end a rotatable sleeve having an angularly disposed deflecting nozzle, and means operable from without the gin flue connection for adjusting said sleeve.

5. The combination with a lint flue, of a gin flue connection having interposed in its discharge end a rotatable sleeve provided with an angularly disposed deflecting nozzle, means accessible from without the gin flue connection for adjusting said sleeve and locking it in the desired adjustment.

6. The combination with a lint flue, of a gin flue connection comprising a pipe fixed to and entering the lint flue at an angle in the direction of the flow of lint in the lint flue, a pipe connection from the gin entering said fixed pipe, a sleeve mounted within the fixed pipe and having the gin pipe telescoped thereinto, said sleeve having its discharge end disposed at an angle to the axis of the fixed pipe, means to hold the sleeve in assembled position between the gin pipe and the fixed pipe, and externally accessible

means to adjust the sleeve angularly about the axis of the fixed pipe.

7. The combination with a lint flue, of a gin flue connection comprising a fixed pipe connected to the lint flue and inclined in the direction of flow of lint through the lint flue, a gin pipe connection of less diameter than the fixed pipe and adapted to project into the open end of the latter, a sleeve telescoped over the end of the gin pipe and disposed within the fixed pipe, a spacer ring connecting the gin pipe and free end of the fixed pipe and providing an annular pocket in which the sleeve is rotatable, a ring mounted on the outer end of the sleeve with a series of equi-distantly spaced threaded holes therein, a slot in the fixed pipe registering with said holes, and a set screw adapted to be inserted through the slots and screwed into any desired one of said holes, the slot being longer and said sleeve having an angularly disposed deflecting end within the inner end of said fixed pipe.

In testimony whereof I affix my signature.

EUGENE MUNGER.
